CLAIM

The ornamental design for a pinch grip garment hanger with indicator and placard, as shown and described.

DESCRIPTION

FIG. 1 is a perspective view of a pinch grip garment hanger with indicator and placard showing my new design;

FIG. 2 is a front view thereof;

FIG. 3 is a rear view thereof;

FIG. 4 is a top view thereof;

FIG. 5 is a bottom view thereof;

FIG. 6 is a side view thereof;

FIG. 7 is an opposite side view thereof;

FIG. 8 is a perspective view of a pinch grip garment hanger with indicator and placard showing another embodiment of my new and ornamental design;

FIG. 9 is a front view thereof;

FIG. 10 is a rear view thereof;

FIG. 11 is a top view thereof;

FIG. 12 is a bottom view thereof;

FIG. 13 is a side view thereof; and,

FIG. 14 is an opposite side view thereof.

The broken line showing of the hanger and lettering is for the purpose of illustrating environmental structure and forms no part of the claimed design.
